D. G. Littlefield.

Magazine Stove.

No 10,448.

Patented Jan. 24, 1854.

UNITED STATES PATENT OFFICE.

DENNIS G. LITTLEFIELD, OF LOWELL, MASSACHUSETTS.

STOVE.

Specification forming part of Letters Patent No. 10,448, dated January 24, 1854; Reissued November 19, 1861, Nos. 1,236 and 1,237.

To all whom it may concern:

Be it known that I, DENNIS G. LITTLEFIELD, of Lowell, in the county of Middlesex and State of Massachusetts, have invented 5 certain new and useful Improvements in Stoves for Heating, which improvements are also applicable to house-furnaces, cooking-ranges, steam-engine boilers, &c.; and I hereby declare the following to be a full, 10 clear, and exact description of the same, reference being had to the annexed drawings, making part of this specification, in which—

Figure 1 is a view of a stove, with my improvements attached, the doors being open to show the interior. Fig. 2, a vertical section through the same. Fig. 3 a view of one of the doors; and Fig. 4 a plan of the conical grate.

20 Stoves for burning anthracite have been contrived in which a reservoir for the coals has been applied immediately over the fire pot in such a position that as the fuel is consumed, that in the reservoir descends and supplies its place. In such cases the ignition has taken place entirely within the fire pot, which in no cases has been perforated to permit the flame to pass through into another chamber surrounding the fire pot, 25 where the unconsumed gases might be ignited in contact with the partially burned coal and the consequence has been that a large portion of the gases produced have passed off unconsumed, causing a great waste 30 of fuel, while the partially consumed coals from which the more volatile and inflammable portions have been expelled, when they reach the interior surface of the pot or the sides of the close fire box are soon cooled 35 and extinguished, the current of air which makes its way up through the fire being insufficient to keep the combustion to a point that would consume all the cinders and more refractory portions of the coal, unless 40 the fire were rushed, when other inconveniences result such as the formation of clinkers and the destruction of the fire pot: the stove in such case requiring frequently to be cleaned out to rid it of these 45 clinkers and unconsumed coals. On this account it has been found impracticable, in any stove heretofore constructed, whether with or without a reservoir for fuel, to maintain the fire for a considerable length 50 of time without the necessity of clearing it

out as before mentioned. It is furthermore well known that the perfect and entire combustion of anthracite can only be effected by causing the hydrogen of the coal as well as the various products of imperfect combustion such as carbureted hydrogen and carbonic oxid to ignite in immediate contact with the solid portions or partially consumed coals, from which the gases have been expelled, the two as it were helping to consume each other.

55 To effect this simultaneous combustion of the waste gases with the carbon of the coals is the object of my invention, which consists in the employment of a cylindrical grated fire pot, with no solid or unperforated sides, against which the partially consumed coals can rest and cool, which cylindrical grate is surmounted by a reservoir for the reception of the gases which arise from the burning of the fresh coal. As this reservoir, which serves also to contain a supply of fuel, is closed at the top the only escape for the gases which it collects is through the cylindrical grate at a point where the solid 60 unconsumed coal is in a state of ignition, these gases are thus inflamed and by the heat thus produced, aid in the combustion of the partially consumed coals which always and under the most favorable circumstances burn much more reluctantly than the fresh coal, as their most inflammable elements have already been dissipated. By carefully collecting these gases in the manner above described and igniting them in 65 immediate contact with the unconsumed portions of the coals I am enabled entirely to consume the latter at the same time that the otherwise waste gases are economized and the fuel is consequently entirely utilized, the ashes falling from the grate at the bottom free from cinders and clinkers. This latter peculiarity of my stove, viz, the entire freedom from clinkers, is believed 70 to be due to the fact that the hottest part of the fire is upon the exterior, all around the grate, as this is the point where the gases are burned and not as in all other stoves with which I am acquainted, in the center. The heat is thus kept all through the fire pot at 75 a height sufficient to promote constant combustion. In stoves as heretofore constructed however the heat accumulates in the center of the fire, while at the sides where it comes in contact with the surface 80

of the fire pot, the coals are cooled so rapidly that they are soon extinguished, and the consequence is a great amount of cinder, which renders it necessary frequently to 5 clean out the stove and start the fire afresh.

In conical grates as heretofore constructed the radial bars pass directly from the center to the circumference and the ashes and small cinders become arched over the 10 openings between the grate bars and thus slide down the latter without being materially disturbed on their way down.

In my improved grate the bars instead of being continuous from the center to the 15 circumference are interrupted by two or more rings, and the short bars which unite these rings are so arranged, that those upon one side of the rings are placed opposite to the spaces upon the other side, and thus the 20 cinders are prevented from arching or if the arch be formed it is immediately broken up as the cinders descend along the bars of the grate.

To enable others skilled in the art to make 25 and use my invention I will proceed to describe its construction and operation.

A is the base of the stove immediately above which is the ash pit B.

D is the bed plate having a cylindrical 30 opening in its center over which are placed the grate and fire pot which rest upon a ring α of the form represented in Fig. 2. The flange b rises a short distance above the bottom of the fire pot, which distance should 35 be slightly less than the average diameter of the coal to be burned and consequently varies with the size of the latter. The fire pot or cylindrical grate E rests immediately upon a ledge of the ring α . The bars d 40 of the grate are of a peculiar shape being wider at the top than at the bottom so that the spaces c between them are widest at the bottom. This form of the grate bars, though not absolutely requisite, is highly 45 important to the most successful operation of my stove, as the flame of the burning gases is thrown thereby much lower than would be the case if the spaces were widest at top, and the hottest part of the fire is 50 thus always at the bottom of the grate and at the exterior which is the reverse of what ordinarily takes place.

The height of the bars of the cylindrical 55 grate should be proportioned to the circumference of the latter, for should this height exceed a certain limit the coals when they reach the bottom of the grate would be too far removed from the influence of the burning gases and thus the object of my invention 60 would be defeated.

F is a reservoir which is placed immediately over the fire pot, to the top of which it is accurately fitted. The main object of 65 this reservoir is to afford a receptacle for the waste and unconsumed gases, which are

thrown off during the first ignition of the anthracite and which in stoves as at present constructed pass off through the smoke flues unconsumed. This reservoir also serves the purpose of a magazine or receptacle for the fuel, where it is desired to feed the fire but once in twenty-four or forty-eight hours and if sufficiently enlarged may be made to contain a supply for a much longer period. The reservoir is furnished with a cover H, 70 which is closed when the cover is in operation. Surrounding the above described cylindrical grate is another cylinder L, which forms the exterior of the stove and between which and the fire grate is the fire chamber G. It is in this chamber that the gases are burned as they issue through the openings between the grate bars d . It has openings f upon every side, which like those in the doors are glazed with isinglass, and thus 75 the stove when in operation presents the cheerful appearance of an open fire, a large sheet of flame issuing constantly from between the grate bars. The exterior cylinder 80 of the stove is furnished with a cover I, which is to be removed when the reservoir 85 is to be replenished.

K is the smoke discharge pipe.

In Fig. 3 is seen a representation of the sliding doors which are shown open at M, 95 Fig. 1. g' are sliding draft doors through which air is admitted beneath the grate and by opening or closing which the intensity of the fire is regulated. In order to produce a tight joint between the door and the stove 100 and at the same time to permit the former to slide freely in the grooves which hold it, the bottom of the door is slightly sloped off from the center h , (Fig. 3,) to both corners i , which gives it the required tendency to 105 hang inward. This will appear from an inspection of Fig. 3, for as the door is curved to correspond with the cylinder of the stove, its center of gravity will fall within the curve, consequently when it rests upon the 110 point h its tendency will be inward or toward the stove.

In Fig. 4 is seen a plan of my improved conical grate. $k k'$ are rings concentric with the exterior circle of the grate. The bars l 115 from the center to the ring k are opposite to the spaces between the rings k and k' , which again fall opposite to the bars of the outer course, and the arching of the cinders over the spaces between the bars is thus 120 prevented as before stated.

Operation: The fire is kindled within the cylindrical grate E, the reservoir is filled with coal and the cover I is closed. The interior cover may be left open a short time 125 until the fire is kindled to prevent smoking the isinglass in the sides of the stove. It is then also closed. As the combustion continues the fuel sinks down, all within the fire pot below the top of the grating being 130

fully ignited, having parted with its more inflammable portions while subjected to the heat of the fire, immediately above the top of the spaces in the cylindrical grate. At 5 this point, about the line α α of Fig. 2, the coal is fully ignited, although the combustion is very slow until in descending it reaches the top of the spaces c , when it begins to consume freely. The gases and 10 products of imperfect combustion which were collected within the cylindrical grate being poured out through the spaces in the pot are inflamed and thus aid in the combustion of the remaining portions of the 15 fuel, which as before stated always burns reluctantly unless subjected to a great draft, and is easily extinguished when it is allowed to rest against the unperforated sides of an ordinary fire pot. By perforating 20 this fire pot or making it of grating and causing the combustion and draft to be through the spaces in the grating, and by forcing the unconsumed gases to be ignited in contact with the coal, both are entirely 25 consumed and the various deleterious gases, which so often poison the atmosphere of our buildings when heated with anthracite, are thus entirely consumed and a great economy of fuel results. In open grates more or less 30 of these unhealthy gases escape into the room, and in close stoves, where the combustion is always more or less imperfect, they pass off through the smoke flues.

Thus far my invention has been described 35 in its applicability to stoves for heating

purposes only. I do not however intend to limit myself to this use of it alone, but to employ it wherever it may be advantageously applied, particularly to house furnaces, cooking ranges, steamboat boilers, &c. In the latter case the grate bars might 40 all be water spaces or the fire pot could be made of tubes communicating above and below with the boiler, these are details however which will hereafter be determined and 45 need not now be dwelt upon.

It is evident that it is not essential that the fire pot be cylindrical, though this is the form which I prefer. It may be of any other form, oval square, &c., provided the 50 essence of the invention remain the same, viz., the grated fire pot with the combustion upon both of its sides, together with any suitable receptacle to collect the gases and to throw them upon the burning coal.

What I claim as my invention and desire 55 to secure by Letters Patent is—

The cylindrical grated fire pot E in combination with the gas receptacle F, constructed and operating in the manner substantially as described, by which I am enabled to burn the gaseous and more inflammable elements of the coal in immediate contact with its more refractory portions, and thus insure the complete combustion of them 60 both.

DENNIS G. LITTLEFIELD.
